(57) **CLAIM**

The ornamental design for a tube tag, as shown and described.

DESCRIPTION

FIG. 1 is a top, front, left side perspective view of a tube tag; the top, right side perspective view being a mirror image thereof, therefore not shown;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom, rear, right side perspective view thereof; the bottom, rear, left side perspective view being a mirror image thereof, therefore not shown.

The shade lines in the Figures show contour and do not claim surface ornamentation or treatment.
